ATTORNEYS

UNITED STATES PATENT OFFICE.

ADOLPH RUBIN, OF ST. LOUIS, MISSOURI, ASSIGNOR TO SIEBER PRODUCTS MANUFACTURING COMPANY, OF ST. LOUIS, MISSOURI, A CORPORATION OF MISSOURI.

LOOSE-LEAF BINDER.

Application filed June 11, 1927. Serial No. 198,230.

This invention relates to loose leaf binders of the type that comprise two opposed leaf-clamping members or jaws between which the bundle of leaves is interposed, and a plurality 5 of rigid posts on one of said leaf-clamping members that pass through holes in the leaves and thus prevent the leaves from pulling out of the binder.

One object of my present invention is to 10 provide a loose leaf binder of the general type mentioned, that is equipped with a novel means for detachably connecting the posts to the leaf-clamping member arranged in opposed relation to the leaf-clamping member 15 that carries the posts, said means consisting of individual locks or retaining devices carried by the leaf-clamping member to which the posts are detachably connected and constructed so that they can be moved easily into 20 locking engagement with the posts.

Another object is to provide a loose leaf binder of the kind referred to in which the leaf-clamping member that carries the locks or retaining devices for the posts, is combined with the back of the binder in such a way that it will be sure to move into operative relationship with the posts when the leaf-clamping members are moved into opposed relationship to clamp the leaves together. 25

And still another object is to provide a loose leaf binder that is inexpensive to manufacture and easy to assemble.

Figure 1 of the drawings is an end elevational view of my improved loose leaf binder, showing the leaf-clamping members separated so as to permit the leaves to be inserted or removed. 35

Figure 2 is a front view of the back of the binder and the hinged leaf-clamping members carried by said back, illustrating one of the post-locks in its operative position and the other in its inoperative position. 40

Figure 3 is a plan view of the parts shown 45 in Figure 2.

Figure 4 is a longitudinal sectional view of the binder, taken on the line 4—4 of Figure 2, looking in the direction indicated by the arrows. 50

Figure 5 is an enlarged transverse sectional view, taken on the line 5—5 of Figure 2, looking in the direction indicated by the arrows. 105

Figure 6 is a perspective view of one of the post-locks or retaining devices.

Figure 6^a is a perspective view of said post-lock before it has been bent in the operation of mounting it on the leaf-clamping member on which it slides; and 55

Figure 7 is an enlarged side elevational view of a portion of the leaf-clamping member on which said post-lock slides. 60

Referring to the drawings which illustrate the preferred form of my invention, A designates the back of the binder which is preferably composed of a piece of sheet-metal 65 curved slightly in transverse cross-section as shown in Figures 1 and 5. B designates the covers of the binder, usually formed from pieces of stiff cardboard or other suitable material joined by flexible devices to the back A. 70 C and C' designate two leaf-clamping members or jaws that are hinged to the back A and D designates a plurality of posts rigidly connected to the leaf-clamping member C and adapted to be inserted through holes in 75 the leaves α confined between the leaf-clamping members C and C' of the binder.

The posts D are provided at their upper ends with annular grooves 1 and the leaf-clamping member C' is provided in its outer 80 edge or free edge with open-ended notches 2 for receiving the grooved portions of the posts D when the leaf-clamping members of the binder are arranged in opposed relationship, as shown in Figure 5, the notches 2 being 85 so arranged that the reduced portions of the posts, produced by the grooves 1, will fit in said notches and the heads 3 of the posts will lap over the outer side of the leaf-clamping member C', and thus prevent said member 90 from being moved laterally away from the leaf-clamping member C. The grooved or reduced portions of the posts D are retained in the notches 2 in the leaf-clamping members C' by post-locks or retaining devices E 95 that are slidably mounted on the leaf-clamping member C'. The post-locks E can be constructed in various ways without departing from the spirit of my invention, but they are preferably slidably mounted on the leaf-clamping member C' and are provided with 100 retaining portions 4 that are adapted to be moved into overlapping relationship with the grooved end portions of the posts D, so as to prevent the posts from pulling upwardly 105 out of the notches 2 in the leaf-clamping member C'. Each of the post-locks E preferably comprises a substantially channel-

shaped portion 5 at one end of the retaining portion 4 that embraces the leaf-clamping member C', the side legs of said channel-shaped portion 5 being disposed at a slight angle to each other, as shown in Figure 6, so as to exert sufficient frictional pressure on the leaf-clamping member C' to hold the device in adjusted position. The retaining portion 4 of the device is hollow so that it will surround horizontally-disposed guides 6 and 6^a on the leaf-clamping member C' arranged at opposite sides of the notch 2. When the post-lock E is in its inoperative position, as shown at the left of Figure 3, the hollow post-retaining portion 4 of said device will surround only the guide 6. When said device E is moved longitudinally of the leaf-clamping member C' into its operative position, shown at the right of Figure 3, the hollow portion 4 on said device will telescope over the guide 6^a on the leaf-clamping member C', and accordingly, will securely hold the post C with which it cooperates and prevents said post from moving upwardly out of the notch 2. The retaining portion 4 of the locking device E is of such length that when said device is arranged in its operative position, said portion 4 will bridge the notch 2 and will embrace the two guides 6 and 6^a at opposite sides of said notch. It is immaterial, so far as my broad idea is concerned, how the post-lock E is constructed, but I prefer to form the hollow post-retaining portion 4 of the device in such a way that it can be slipped downwardly over the upper edge of the leaf-clamping member C' and then bent from the position shown in Figure 6^a into the position shown in Figure 6, so as to cause the two side pieces of said portion to embrace the leaf-clamping member C', and a flange 7 on one of said side pieces to project inwardly into a horizontal slot 6^b under the two guides 6 and 6^a on the member C', the flange 7 cooperating with the guides 6 and 6^a to prevent the device E from moving upwardly. At one end of the device E is a finger piece 8 that the operator grasps to move said device. A post-retaining device E of the construction above described will remain in the position into which it has been moved, due to the fact that the side legs of the channel-shaped portion 5 of same securely grip the leaf-clamping member C'; it is easy to apply, and as it comprises a hollow portion 4 that embraces either one or both of the guides 6 and 6^a on the member C', it cannot become accidentally disengaged from said member.

The leaf-clamping members C and C' are hinged to the back A preferably by integral eyes or the like on the back A which receive pintle portions on the leaf-clamping members. As shown in Figures 4 and 5, the leaf-clamping member C is provided at its inner edge with two horizontally-disposed pintle portions 9 which are produced by open-ended

slots 9^a formed in the edge of said member C. The back A is provided with two integral eyes 10 that are adapted to be combined with the pintle portions 9 of the member C by inserting said eyes 10 in the ends of the slots 9^a and then moving the back A longitudinally of the member C, so as to cause the pintle portions 9 to enter the eyes 10, as shown in Figure 4. Thereafter, a projection 11, which is arranged intermediate the ends of the back A, is bent laterally into an open-ended notch 12 in the inner edge of the leaf-clamping member C, so as to prevent said member C from moving longitudinally of the back A in a direction to disengage the eyes 10 from the pintle portions 9. A similar means is used to hinge or connect the leaf-clamping member C' to the other edge of the back A, except that the hinges between the member C' and the back A are so constructed that when the binder is open, as shown in Figure 1, the leaf-clamping member C' will be maintained in such a position that when said leaf-clamping member is swung to the left, looking at Figure 1, to cause the grooved portions of the posts D to enter the open-ended notches 2 in the member C', said member C' will be sure to line up properly with the grooves 1 in the posts D. In other words, instead of providing the back with circular eyes similar to the eyes 10 which are of such diameter that they can turn freely on pintle devices on the leaf clamping member, I provide the back with substantially flat eyes 13 that embrace pintle portions 14 on the member C' which are of only slightly less thickness than the width of the eyes 13, the pintle portions 14 being similar to the pintle portions 9 on the other leaf-clamping member. After the eyes 13 on the back A have been inserted in the open-ended notches 14^a in the edge of the leaf-clamping member C', said member is moved longitudinally of the back so as to cause the pintle portions 14 to enter the eyes 13, thus causing the leaf-clamping member C' to be hinged to the back A in such a way that it is capable of a slight rocking movement relatively to said back, but will be maintained in a position at substantially right-angles to the back when the binder is open, and consequently, will line up properly with the grooves 1 in the posts D when the leaf-clamping member C' is moved laterally into opposed relationship with the leaf-clamping member C. After the eyes 13 on the back have been engaged with the pintle portions 14 on the leaf-clamping member C', a projection 11^a on the back is bent laterally into an open-ended notch 12^a in the leaf-clamping member C' so as to lock the parts A and C' together or prevent them from moving longitudinally of each other in a direction to withdraw the pintle portions 14 from the eyes 13. It is, of course, obvious that any desired number of pintle

portions and cooperating eyes can be used to hinge or pivotally connect the leaf-clamping members C and C' to the back A, and that any other means than the cooperating projections 11, 11^a and notches 12 and 12^a can be used to prevent relative longitudinal movement between the back and the leaf-clamping members after the eyes and the pintle portions on said elements have been 10 engaged with each other.

A loose leaf binder of the construction above described can be manufactured at a low cost, due to the fact that the back A and leaf-clamping members C and C' can be constructed from sheet-metal by simple stamping operations, or by the use of suitable dies; the leaf-clamping members can be combined quickly and easily with the back A of the binder; the back A can be covered with cloth, 20 leather or any other material, such as is generally used to encase the backs of loose leaf binders prior to the operation of joining the leaf-clamping members to the back; the posts D of the binder can be attached quickly and 25 easily to the leaf-clamping member C', due to the fact that a separate post-lock or retaining device E is provided for each post, and another desirable feature of such a binder is that the leaf-clamping member C' 30 will assume such a position when the binder is open that the open-ended notches 2 in said member will move into operative relationship with the grooved portions of the posts in the operation of closing the binder, the 35 hinges between the leaf-clamping member C' and the back A being of such form that the leaf-clamping member C' cannot swing downwardly into a position at the rear edges of the leaves on the posts D after the binder 40 has been opened to facilitate the insertion or removal of the leaves.

Having thus described my invention, what I claim as new and desire to secure by Letters Patent is:

1. A loose leaf binder, comprising leaf-clamping members, posts rigidly attached to one of said leaf-clamping members and provided with grooved portions that are adapted to be positioned in notches in the other leaf-clamping member, and individual retaining devices for said posts slidingly mounted on the notched leaf-clamping member and adapted to be moved into engagement with the grooved portions of said posts.

2. A loose leaf binder, comprising leaf-clamping members, a post carried by one of said leaf-clamping members, a notch in the other leaf-clamping member adapted to receive the end portion of said post, a retaining device for said post slidingly mounted on said notched leaf-clamping member and provided with a substantially channel-shaped portion that embraces and snugly grips said leaf-clamping member, and a part on said 55 retaining device that is adapted to be ar-

ranged crosswise of said notch so as to hold said post in engagement with said notched leaf-clamping member.

3. A loose leaf binder, comprising leaf-clamping members, a post carried by one of said leaf-clamping members, a notch in the other leaf-clamping member adapted to receive the end portion of said post, a retaining device for said post slidingly mounted on said notched leaf-clamping member and 70 provided with a substantially channel-shaped portion that embraces and snugly grips said leaf-clamping member, and a part on said retaining device that is adapted to be arranged crosswise of said notch so as to hold said post in engagement with said notched leaf-clamping member, said retaining device having a part that is arranged in a longitudinally-disposed slot in said notched leaf-clamping member.

4. A loose leaf binder, comprising leaf-clamping members, a post carried by one of said leaf-clamping members, a notch in the other leaf-clamping member for receiving the end portion of said post, guides at the opposite sides of the notch in said leaf-clamping member, and a lock for said post slidingly mounted on said notched leaf-clamping member and provided with a substantially tubular portion that is adapted to telescope over said 85 guides.

5. A loose leaf binder, comprising a sheet-metal back provided with integral eyes, a leaf-clamping member provided adjacent one of its edges with notches that form pintles which are adapted to be inserted in said eyes by moving said back and leaf-clamping member longitudinally of each other relatively in one direction, and a part on said back that is adapted to be bent laterally into an opening in the leaf-clamping member to prevent withdrawal of said pintles from said eyes.

6. A loose leaf binder, comprising a back, leaf-clamping members hinged to said back, posts rigidly connected to one of said leaf-clamping members and provided with grooved portions, notches in the other leaf-clamping member arranged so as to receive the grooved portions of said posts, and post locks on said notched leaf-clamping member, 110 the hinges between said back and notched leaf-clamping member being constructed so as to hold said member in a position at substantially right-angles to the back when the binder is open.

7. A loose leaf binder, comprising a sheet-metal back, sheet-metal leaf-clamping members, hinges for joining said leaf-clamping members to said back formed by integral portions on said elements that are loosely engageable with each other by endwise movement, means for preventing said leaf-clamping members from moving longitudinally relatively to said back after the engagement thereof, posts carried by one of said leaf- 125

clamping members, and locks for said posts slidingly mounted on the other leaf-clamping member.

8. A loose leaf binder, comprising a sheet metal back, sheet-metal leaf-clamping members, hinges for joining said leaf-clamping members to said back formed by integral portions on said elements that are loosely engageable with each other by endwise movement, means for preventing said leaf-clamping members from moving longitudinally relatively to said back after the engagement

thereof, a post carried by one of said leaf-clamping members, a lock for said post slidably mounted on the other leaf-clamping member and provided with a substantially channel-shaped portion that embraces said last-named leaf-clamping member, said last named leaf-clamping member being slotted, and a part on said post lock adapted to be bent so as to force it into the slot of said leaf-clamping member.
